FINGER RING

Joseph W. Gittler, Philadelphia, Pa.

Application April 7, 1954, Serial No. 29,892

Term of patent 14 years

(Cl. D45—10)

To all whom it may concern:

Be it known that I, Joseph W. Gittler, a citizen of the United States, residing at Philadelphia, in the county of Philadelphia and State of Pennsylvania, have invented a new, original, and ornamental Design for a Finger Ring, of which the following is a specification, reference being had to the accompanying drawing, forming a part hereof.

Fig. 1 is a perspective view of a finger ring, showing my new design; and

Fig. 2 is an edge view thereof with the lower portion omitted for convenience of illustration only.

I claim:

The ornamental design for a finger ring, as shown.
